UNITED STATES PATENT OFFICE.

HENRY KAPNECK, OF WASHINGTON, DISTRICT OF COLUMBIA.

DESIGN FOR A COMB.

Application filed December 6, 1923. Serial No. 7,967. Term of patent 7 years.

To all whom it may concern:

Be it known that I, HENRY KAPNECK, a citizen of the United States, residing at Washington, in the District of Columbia, have invented a new, original, and ornamental Design for Combs, of which the following is a specification, reference being had to the accompanying drawing, forming part thereof.

The figure is a plan view of one side of a comb showing my new design.

I claim:

The ornamental design for a comb as shown.

In testimony whereof I affix my signature.

HENRY KAPNECK.
